J. A. ALLISON,
STARTING APPARATUS FOR EXPLOSIVE ENGINES,
APPLICATION FILED FEB. 16, 1912.

1,151,151.

Patented Aug. 24, 1915.

UNITED STATES PATENT OFFICE.

JAMES A. ALLISON, OF INDIANAPOLIS, INDIANA, ASSIGNOR TO THE PREST-O-LITE COMPANY, OF INDIANAPOLIS, INDIANA, A CORPORATION OF NEW YORK.

STARTING APPARATUS FOR EXPLOSIVE-ENGINES.

1,151,151.

Specification of Letters Patent. Patented Aug. 24, 1915.

Application filed February 16, 1912. Serial No. 678,001.

To all whom it may concern:

Be it known that I, JAMES A. ALLISON, a citizen of the United States, residing at Indianapolis, Marion county, and State of Indiana, have invented and discovered certain new and useful Improvements in Starting Apparatus for Explosive-Engines, of which the following is a specification.

My said invention consists in an improved construction and arrangement of parts of devices for starting explosive engines, particularly automobile engines, and it relates especially to that class of starters which employs a power medium such as an explosive gas, all as will be hereinafter more fully described and claimed.

Referring to the accompanying drawings, which are made a part hereof and on which similar reference characters indicate similar parts, Figure 1 is a side view of the front end of an automobile illustrating my improved engine starting means applied thereto, Fig. 2 a detail horizontal section through the dash of the vehicle showing those parts 25 of the apparatus which are attached to said dash in elevation, Fig. 3 a central section through the valve casing on the dotted line 3-3 in Fig. 2, Fig. 4 a perspective view of the inner end of the valve stem and parts 30 adjacent thereto, Fig. 5 a detail edge view of the pressure regulating valve on the acetylene tank, Fig. 6 a view showing a modified form.

In said drawing the portions marked A 35 represent the automobile frame, B the engine and C the acetylene or power medium supply tank, which parts may be of any common or approved construction. The engine shown is of the four cylinder type and the upper ends of the cylinders are shown in elevation to illustrate the intake manifold b and the connection therewith, which forms a feature of my said invention. The power medium tank shown is of the type known as the "Prest-O-Lite" 45 tank, but may be any approved type and preferably has an automatic pressure regulator c attached to the discharge end thereof.

The valve casing 10 is mounted on the dash-board under the hood, as shown, with the valve stem 11 extending through an aperture in said dash. Said aperture is cov-

ered by a face-plate 12 on the front face of said dash, the securing flange of the valve 55 casing and said face-plate being connected through said dash by the same securing bolts 13. Said valve casing is formed with branches leading from opposite sides thereof to one of which a pipe 14 is connected, 60 which leads from the low pressure side of the pressure regulator, and the other of which is connected by a pipe 15 to the intake manifold of the engine. The valve 16 is of a common cylindrical form, somewhat tapered, and mounted in the valve casing, as shown, and is formed with a straight port leading entirely through the same, which when in proper position is adapted to register with the branches leading from each 70 side of the valve casing to establish a free passage-way therethrough. The inner end of said stem has an operating lever 17 mounted thereon and stop pins 18 and 19 are provided on the face-plate 12 for limiting the movement of said lever, in either direction, at a point which will bring the port in the valve to register with the openings in the casing and establish communication through said casing from pipe 14 to pipe 15. 80 When said lever is turned downwardly, as shown in Fig. 3, the passage-way through said valve-casing will be closed and when it is turned horizontally, as shown in Fig. 2, said passage-way will be opened. On the 85 inner end of said valve stem is mounted an arm 20 which turns therewith and is electrically connected by a wire 21 in the magneto circuit (not illustrated). A contact plate 22 is mounted on a ring 23 of insulating material mounted on the valve casing around the inner end of the valve stem and a contact spring 24 carried by the arm 20 is adapted to contact therewith when operating lever 17 is in one of its horizontal positions.

The operation is as follows: The valve is normally closed when the engine is running. When it is desired to stop the engine the operator turns the operating lever to the 100 position shown in Fig. 2 which brings contact spring 24 in contact with plate 22, which operates to ground the magneto circuit through the valve to the machine frame, which stops the sparking and the engine. 105 At the same time communication is estab-

lished from the low pressure side of pressure regulator *c* through the valve-casing and pipes 14 and 15 to the intake manifold *b* of the engine. The last strokes of the engine 5 pistons will draw a charge of the explosive gas from the storage tank through the passage-way thus established into the cylinders. The operator then turns the handle 17 to a vertical position closing the 10 passage-way and leaving a charge of explosive gas in the cylinders while the engine is at rest. When it is desired to start, it is only necessary to turn on the spark, by means of the ordinary switch, which will 15 ignite the explosive and cause an explosion in the appropriate cylinder and start the engine. Should the start secured by the stored charge of acetylene, or other gas employed, be insufficient to continue the engine 20 in motion until the carbureter is working properly the operator turns the handle 17 to the other horizontal position and the gas will feed through pipes 14 and 15 to the intake manifold and the engine be permitted 25 to run on such gas until the carbureter is working properly when handle 17 is turned to a vertical position closing the passage way.

It will be noticed that handle 17 is heavy 30 at its outer end and its normal position hanging vertically from the valve stem, thus providing against accidental opening of the valve.

By means of the apparatus thus described 35 the engine is automatically charged with an explosive gas during the stopping strokes of its pistons and is always ready for starting with the ordinary spark. If the engine should stand dead until the explosive gas 40 charge is wasted through leakage, or from any other cause, it is only necessary to turn the valve so that the passage-way will open directly from the gas tank to the engine when said gas will flow into the intake 45 manifold in sufficient quantities to ignite and start the engine. The grounding, or short circuiting, contact between the magneto circuit and the valve mechanism will only be made at one horizontal position of said valve 50 and this is a position to which said valve is turned when the engine is to be stopped. Whenever the explosive gas is desired in the engine while the engine is running, or an additional supply while starting, said valve is 55 turned in the other direction so that the passage is opened without interfering in any way with the magneto circuit. The stop pins 18 and 19 serve to limit the movement in each direction. Pin 19 serves to 60 limit its movement when turned to open the way and ground or short circuit the magneto, and pin 18 serves to limit said movement when moving the other way to open the way without grounding the magneto.

65 In Fig. 6 the pipe leading from the explosive

gas supply tank to the engine is shown as connected directly to the supply end of the tank, the pressure regulator shown in the preferred form being omitted. This form may be used when preferred or found 70 advantageous. It is understood, of course, that the usual regulating means within the tank may be found all that is necessary for the purposes of this invention under some conditions.

Having thus fully described my said invention, what I claim as new and desire to secure by Letters Patent, is:

1. An apparatus for starting explosive engines comprising an explosive medium supply, a pipe leading from said supply to the engine, a valve interposed in said pipe, means for short circuiting the magneto connected with said valve and operated from a single operating means, and means for supplying the explosive medium to the cylinders without operating said short circuiting means, substantially as set forth. 80

2. An apparatus for starting explosive engines comprising an explosive gas supply, a pipe leading from said supply to the engine, a controlling valve in said pipe formed to open a communication through said pipe at different positions of said valve, and means for short circuiting the magneto arranged 95 to be operatively connected only when said valve is in a single one of said open positions, substantially as set forth. 90

3. A starting apparatus for explosive engines comprising an explosive gas supply, a pipe leading therefrom to the engine, a valve interposed in said pipe formed to have different open positions, a connection between said valve and the magneto circuit, a short circuiting means, and a contact arm 100 adapted to be operated to contact with said short circuiting means when said valve is swung to only one open position, substantially as set forth. 105

4. A starting apparatus for explosive engines comprising an acetylene storage tank, a pressure regulator thereon, a pipe leading from said pressure regulator to the engine, a valve interposed in said pipe attached to control the passage therethrough and having different open positions, and short circuiting means for the magneto circuit connected to be operated by said valve in but one of said open positions, substantially as set forth. 110

5. An apparatus for starting explosive engines comprising an acetylene storage tank, a pipe leading therefrom to the engine, a valve interposed in said pipe for controlling the passage-way therein and formed to have 125 different open positions, a contact plate carried on the valve casing and connected with the machine frame, and an arm carried on the valve stem and electrically connected in the magneto circuit, said plate and arm be- 120 130

ing positioned to contact when said valve is in but one of its open positions, substantially as set forth.

6. A starting apparatus for explosive engines comprising an explosive medium supply, a pipe leading therefrom to the engine, a valve in said pipe arranged with different open positions, and a handle for operating said valve arranged with a weighted end to 10 hang downwardly during the closed position of said valve, substantially as set forth.

7. An apparatus for starting explosive engines comprising an explosive gas supply, a pipe leading therefrom to the engine, a 15 valve interposed in said pipe formed to have different open positions, means for operating said valve, an arm on the stem of said valve connected in the magneto circuit, a plate adjacent thereto connected with the 20 machine frame, and means for forming a

contact between said arm and said plate when the valve is in but one of its open positions, substantially as set forth.

8. A starting apparatus for explosive engines comprising an explosive medium supply, a pipe leading therefrom to the engine, a valve in said pipe with different open positions, and means for grounding or short circuiting the magneto arranged to be operatively connected when said valve is in 25 but one of its open positions, substantially as set forth.

In witness whereof, I have hereunto set my hand and seal at Indianapolis, Indiana this 12th day of February, A. D. nineteen 35 hundred and twelve.

JAMES A. ALLISON. [L.S.]
